UNITED STATES PATENT OFFICE.

WALTER H. STOEHR, OF CHENEY, KANSAS.

FOUNTAIN-BRUSH.

1,135,739.

Specification of Letters Patent. Patented Apr. 13, 1915.

Application filed June 15, 1914. Serial No. 845,222.

To all whom it may concern:

Be it known that I, WALTER HERMAN STOEHR, a citizen of the United States, residing at Cheney, in the county of Sedgwick and State of Kansas, have invented certain new and useful Improvements in Fountain-Brushes, of which the following is a specification.

This invention relates to painting machines and more particularly to a fountain brush, and has for its object to provide a device of this character of simple and efficient construction embodying a nozzle positioned between the bristles of the brush and communicating with a feed-pipe, and a fabric covering for the nozzle primarily designed to regulate the flow of paint and assist the bristles in spreading it.

With this and other objects in view, the invention consists in the novel construction, arrangement and the formation of parts as will be hereinafter specifically described, claimed and illustrated in the accompanying drawings, in which,

Figure 1 represents a side elevation of the painting machine, partly broken away, Fig. 2 represents a longitudinal sectional view therethrough, and, Fig. 3 represents a perspective view of the nozzle and the covering therefor, partly broken away, removed from the brush.

Referring to the drawings in detail, wherein similar reference numerals designate corresponding parts throughout the several views, the numeral 5 indicates a suitable tank or reservoir provided with a handle or shoulder-strap 6 whereby the device may be conveniently carried by the operator. The tank is also provided with a suitable filling opening and an outlet pipe 7 in its lower end controlled by a valve 8 and communicating with the feed-pipe 9 preferably of flexible tubing. The feed-pipe or tube 9 is connected at its outer end with

feed-pipe 10 communicating with the nozzle 11 and extending longitudinally through an opening in the handle 12 of the brush having the usual head 14. Bristles 13 are secured in the head 14 and the latter is formed with a recess constituting a seat 45 for the nozzle 11 arranged substantially centrally between the bristles 13.

A covering 15 of a suitable fabric such as canvas or similar material of durable and inexpensive character is positioned over the nozzle 11 between the latter and the wall and the seat in the brush-head 14. The free edges 16 of the covering are extended to a point nearly adjacent to the free ends of the bristles 13 and the edges thereof are frayed 55 to provide a plurality of threads extended parallel with the bristles 13. The portions of the fabric 15 adjacent the threads 16 normally lie in contact and regulate the flow of liquid to the bristles 13 and materially 60 assist the latter in spreading and distributing the paint.

What I claim is:

A fountain brush comprising a handle having a longitudinal opening therethrough and an integral head having a transversely extending seat communicating with said opening; a feed-pipe positioned within said longitudinal opening, a nozzle positioned within said seat and communicating 70 with said feed-pipe, bristles secured in said head, and a fabric covering positioned within said seat under said nozzle, extending to a point nearly adjacent the free ends of the bristles and having the edges thereof 75 frayed to provide a plurality of threads extending parallel with the bristles.

In testimony whereof I affix my signature in presence of two witnesses.

WALTER H. STOEHR.
